INVENTOR
Henry S. Leggett
BY *Joe H. Leggett*
ATTORNEY

UNITED STATES PATENT OFFICE.

HENRY S. LEGGETT, OF BROOKLYN, NEW YORK.

ADJUSTABLE BRACKET FOR CLOTHESLINES.

Application filed May 24, 1926, Serial No. 111,087. Renewed August 24, 1927.

This invention relates generally to clotheslines used for hanging out clothes and the like, to be dried after washing, the invention having more particular reference to a novel type of clothesline device.

The invention has for an object the provision of an improved clothesline device easily manipulated in the window, and making the work of hanging out the clothes thereon less arduous.

A further object of the invention is the provision of an improved clothesline device of simple construction, and novel arrangement of parts.

For further comprehension of the invention, and of the objects and advantages thereof, reference will be had to the following description and accompanying drawing, and to the appended claims in which the various novel features of the invention are more particularly set forth.

Fig. 1, of the drawing, is a perspective view of my improved clothesline device, as it would appear when in position to be used.

Fig. 2 is a side elevational view of the operating mechanism as used in connection with my improved clothesline device.

Fig. 3, is a front elevational view thereof.

Fig. 4, is a fragmentary perspective view of the tubular member.

Fig. 5, is a side elevational view, partly in section, so as to expose certain interior parts, of the self adjusting pulley as used in connection with my improved clothesline device.

Fig. 6, is a front elevational view thereof.

Fig. 7, is a fragmentary perspective view of the operating mechanism illustrating a modification thereto.

As here embodied my improved clothesline device comprises an operating mechanism, consisting of a support 10, or bracket, having a threaded extremity 11, and a vertically disposed element 12, adapted to ro-

tatively support a hollow cylindrical member 13. The pulley 14, is rotatively mounted in the sheave 15, such as is common to pulleys used to support clotheslines, and the like, and is pivotally attached, as at 15', to

a support 16' attached to the extremity of the supporting shaft 16, provided with a handle element 17', and is slidably mounted in the tubular member 17, provided with an elongated slot 18, extending from one ex-

tremity of the tubular member 17 inward therefrom through the enlarged extremity

18' of the tubular member 17, as at 19', longitudinally thereto, and transversely thereto, as at 20', any suitable distance, and having bayonet slots 19 suitably formed and 60 intercommunicative with the elongated slot 18, adapted to engage a suitably projecting element 20, of the supporting shaft 16, so as to hold the said supporting shaft in any desired extended position therefrom. The 65 tubular member 17, has attached thereto, extended members 21, which are also attached to the hollow cylindrical member 13, so as to rigidly support the tubular member 17. A frame is provided, consisting of a block 70 23 rigidly attached to the above mentioned support 10. Said block has attached thereto, as at 24, by screws, bolts, or the like, a U-shaped bracket 25. The U-shaped bracket extends from the sides of the block 23 and 75 is adapted to support, as shown at 26, one extremity of a pin 26'; the other end of the pin 26' being supported by the block 23 as indicated by the numeral 25'. The said pin 26' is adapted to engage notches 22' located in the rod 22. The operating rod 22, is pivotally attached, at one extremity, as at 27' to one of the extended members 21, and is provided with a handle 27, located at the other extremity thereof. 80

It should be understood that with the above described construction the operating rod 22 may be manipulated to swing the pulley 14 through the window into the house to permit the end of the clothesline 28, to be 90 swung inward so that clothes or the like, may be easily and readily attached to or removed from the said clothesline 28, by a person standing at the window 29. It being understood that the support 10, is attached 95 to the frame 30, of the window 29, by means of the above mentioned threaded extremity 11.

The clothesline 28, is also extended over the pulley 31 rotatably mounted in the 100 sheave 32 rigidly attached to the arm 33 which is pivotally attached, at its upper extremity, as at 34 to the pin 35, attached to the support case 36, of box-like construction, so as to protect the pulley 31 and the connected parts from the rain. The support case 36, has suitably attached thereto, coil spring 37, of the tension type, which is also attached to the arm 33, so as to permit the pulley 31, to pivot or swing forward, when the above mentioned pulley 14 is swung, in the manner as above described and set forth. 110

The support case 36 is pivotally attached, as at 38, to the vertically extended element 39 of the support pin 40, provided with a threaded extremity 41, as a means of pivotally attaching the support case 36, to any suitable and convenient object 42, clothes pole, or the like. The latter described construction being such as will permit the support case 36 to pivot, as may be required 10 when the handle 27, is manipulated as above set forth, so as not to disengage the clothes-line 28, with the pulleys 14 and 31. It will be clearly understood that the coil spring 37, has the necessary tension to hold my improved clothesline device, in the position as 15 clearly shown in Fig. 1, of the accompanying drawing.

Referring in particular to Fig. 7, of the accompanying drawing in which I have 20 illustrated a modification of my improved device, the coil spring 43', is positioned over the operating rod 22', and is located between the block 23', and the extended member 21', to which the operating rod 22' is pivotally 25 connected, so as to normally hold the pulley 14 in an extended position, as illustrated in Fig. 1, and so as to relieve the required tension of the coil spring 37'. The pin 44' is slidably mounted in the block 23', and is 30 adapted to engage apertures 45', suitably located in the operating rod 22'; so as to hold the pulley 14 in any desired position, as may be required when attaching or 35 removing clothes or the like from the clothes-line 28'.

Having thus described my invention, what I claim as new, and desire to protect by Letters Patent of the United States, is as follows:—

40 1. In a clothesline supporting mechanism of the class described, a bracket comprising

a substantially vertical support, a substantially vertical hollow cylindrical member journaled on said support, a tubular member rigidly mounted on said hollow cylindrical member in spaced relation thereto, said tubular member being provided with a longitudinally extending slot and a plurality of bayonet slots communicating therewith, and a shaft slidably mounted in said tubular member, having a projection on one end thereof adapted to be selectively disposed in any one of said bayonet slots to retain said shaft in a desired extended position the free end of said shaft protruding from said tubular member and having a pulley mounted thereon.

2. In a clothesline supporting mechanism of the class described, a bracket comprising a substantially vertical support, a substantially vertical hollow cylindrical member journaled on said support, a tubular member rigidly mounted on said hollow cylindrical member in spaced relation thereto, a shaft slidably mounted in said tubular member 60 adapted to be extended from one end thereof, a pulley mounted on the end of said shaft, a frame mounted on said bracket comprising a block, a catch thereon, and an operative lever pivotally connected with said tubular member and slidably mounted on said block and having notches therein 65 adapted to engage said catch, said operating lever being adapted to be manipulated for rotating said vertical cylindrical member, said tubular member and shaft in unison to position said pulley within a window.

In testimony whereof I have affixed my signature.

HENRY S. LEGGETT.
